(57) **CLAIM**

The ornamental appearance for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface according to a first embodiment.

FIG. 2 is a front view of a second embodiment thereof.

FIG. 3 is a front view of a third embodiment thereof; and, FIG. 4 is a front view of a fourth embodiment thereof.

The dot-dash broken lines define the bounds of the claimed design and form no part thereof.

The evenly spaced broken lines show portions of the graphical user interface that form no part of the claimed design.
